UNITED STATES PATENT OFFICE.

LOUIS BAJETT, OF PLAINFIELD, NEW JERSEY.

BELT-TIGHTENER AND BRAKE FOR SPONGING-MACHINES.

1,226,297.

Specification of Letters Patent.

Patented May 15, 1917.

Application filed September 14, 1915. Serial No. 50,609.

To all whom it may concern:

Be it known that I, LOUIS BAJETT, a subject of the President of France, residing at Plainfield, in the county of Union and State 5 of New Jersey, have invented new and useful Improvements in Belt-Tighteners and Brakes for Sponging-Machines, of which the following is a specification.

This invention relates to apparatus for 10 treating cloth, and particularly to the type of machine which is employed for "sponging" cloth.

In the operation of these machines, the cloth is wound upon a perforated drum and 15 steam is admitted to the interior of the drum so as to find its way through the perforations of the drum and through the layers of cloth, thereby producing in the cloth a steaming or "sponging" effect. In some 20 machines this operation is repeated, and for this reason such machines usually comprise more than one drum such as I describe.

A principal object of my invention is to 25 provide improved means for controlling the operation of the drums in winding the cloth on and off the same.

A further object of the invention is to 30 provide means whereby the driving force applied to the drum may be graduated.

35 A further object of the invention is to provide very simple hand-operated means for effecting the application of the driving means to the drum and for stopping the drums at will.

40 A further object of the invention is to provide a machine for sponging cloth, having a plurality of drums with improved means for controlling the drums in order to facilitate the unwinding of the cloth from one drum, and the winding of the same upon the next drum.

45 Further objects of the invention will appear more fully hereinafter.

The invention consists in the general combination of parts and details hereinafter described, all of which contribute to produce an efficient sponging apparatus.

50 A preferred embodiment of the invention is described in the following specification, while the broad scope of the invention is pointed out in the appended claim.

In the drawing,

Figure 1 is a side elevation of a machine embodying my invention.

55 Fig. 2 is a plan of the machine, the middle portion of the same being broken away.

Referring more particularly to the parts, the machine preferably comprises a frame 10 which is preferably provided with a plurality of drums such as the drums 11 and 12, which are rotatably mounted on the frame in a substantially horizontal position and in parallel relation. These drums 11 and 12 are perforated, and at one end are provided with tubular journals at which 60 steam may be admitted by suitable steam pipe connections 13. I prefer to provide frictional driving means for rotating the drum 11. For this purpose I prefer to provide the shaft 14 of drum 11 with a belt 65 pulley 15, and over this belt pulley 15 a belt 16 passes. This belt normally runs loose so that it is ineffective to drive the drum, but it is ready to be actuated at will by the operator of the machine. For this 70 purpose the lower end of the belt runs loosely around a continuously driven pulley such as pulley 18 which is mounted in the lower part of the frame on a suitable 75 shaft 20.

The cloth is first wrapped upon the perforated drum 11 and then upon the drum 12, and is steamed while on each drum. It is then run off the drum 12 onto a removable roller 21 which is mounted on the frame. 80 This removable roller is preferably provided at one end with a gudgeon 22 which is received in a suitable open bearing or notch on the frame at one side, and the opposite end of this roller is provided with an angular or square socket 23 which may receive an angular or square head 24 on the end of the spindle 25. This spindle 25 is normally pressed inwardly by a spring 26, but has a knob 27 on its outer end by means of which 85 it can be withdrawn so as to disengage the head 24 and enable the roller 21 to be removed with the cloth wound upon it.

In order to control the rotation of the drum 11, I provide frictional means operating in such a way as to enable the driving force for the drum to be applied in a graduated degree. For this purpose, I prefer to employ the belt 16 already referred to, and I provide means for tightening this belt so 100 that it may exert more or less of a driving force on the pulley 18 and which is carried by the shaft 14. To this end I prefer to mount a controlling lever 29 on the frame, said lever having a lower arm 30 carrying a 105 belt-tightening pulley 31 which may come against the side of the belt 15, see Fig. 1.

A counterweight 32 tends to hold this pulley 31 off the belt. A lever 29 is provided with locking mechanism 33 of any suitable construction co-operating with a segment 34 which enables the lever to be locked in different positions corresponding to different driving effects. The upper part of the lever 29 is provided with an adjustable bracket 35, the outer end of which is formed into a brake shoe 36 which lies adjacent to the face of a brake wheel 37. In order to enable the bracket 35 to be adjustable, I prefer to attach it to the lever by means of a slot 38, and an adjusting bolt 39. When the lever 29 is unlocked and thrown toward the right, the belt-tightening pulley 31 will be taken off the belt and the brake 36 will be applied to the brake wheel 37. In this way, evidently, the rotation of the drum can be arrested at any time, and the drum can be brought to a gradual or abrupt stop as may be desired.

I prefer to provide means for enabling the lever 29 to be operated by a treadle as well as by hand. This lever 29 carries a finger lever 40 which controls the locking mechanism 33 and it is, of course, desirable to control this finger lever as well as the lever 29 from the treadle. For this purpose I prefer to provide an operating cord 41 having two branches 42 and 43 disposed near the lever and the branch 42 is attached to an arm of the finger lever 40 and is normally taut, while the branch 43 is normally slack. From this arrangement, when the treadle 44 is depressed, the finger lever 40 will be moved to unlatch the locking device 33, whereupon a continued movement of the treadle will pull the lever 29 by means of the branch cord 43. This direction of movement of the treadle will start the drum rotating. If the treadle is allowed to move in the other direction, the counterweight 32 will apply the brake 36 to the brake wheel 45 and stop the drum.

The shaft 20 is preferably driven continuously by any suitable means such as a sprocket chain 45 which passes around a sprocket wheel 46 on a countershaft 47, which is continuously driven by power; for example, by an electric motor, not illustrated. I prefer to drive the drums 12 and 21 also from this countershaft, and these drums are controlled in such a way that either drum can be rotated independently of the other or stopped while the other drum is rotated. For this purpose I prefer to provide a friction clutch 48 which may be closed or thrown into its open position by any suitable means such as the lever 49, pivotally supported at 50 on a suitable bracket, and this lever is preferably disposed between the drums 11 and 12 and controls the operation of the drum 12. When the clutch 48 is closed, the motion is transmitted from

the shaft 47 by means of a sprocket wheel 51 and a sprocket chain 52 to a sprocket wheel 53 rigid on the shaft 54 of the drum 12.

The handle arm 55 of this lever is provided with suitable locking means 56 for locking the clutch 48 open or closed. A similar arrangement is provided for driving the drum 21, preferably comprising a sprocket chain 57 which passes up around a suitable sprocket wheel 58 with a hub 59 on shaft 25. The lower end of this chain 57 passes around a suitable sprocket wheel on the shaft 47, which normally runs loose but which may be driven from the shaft by closing the clutch 60. This clutch 60 is controlled by means of a clutch lever 61, the handle arm of which is provided with suitable locking mechanism 62 for locking the clutch either closed or open.

I prefer to provide sprocket chains instead of belts in connection with the drums 12 and 21 because the cloth in running onto these drums has already been soaked with steam, and a considerable amount of water may drop or fly off these drums. This water has a bad effect on the operation of the belts but has no bad effect on the operation of the sprocket chains.

In the operation of the machine, the cloth is first wrapped upon the drum 11 where it is steamed or "sponged" by admitting steam through the connection 13. After being steamed on this drum, the outer end of the cloth is then carried over and wrapped upon the drum 12, a few turns of the drum 12 being made by rotating the drum by hand through the agency of the hand wheel 63 carried by the shaft of this drum. The clutch 48 is then closed and this drives the chain 52 and rotates the drum 12 by power. While on this drum, the cloth is steamed by admitting steam through the connection 13. After being sufficiently steamed on this drum, the lever 55 is operated so as to open the clutch 48, and the cloth is then wrapped upon the drum or removable roller 21, the first few turns being made by means of a hand wheel 64 on the spindle 25 of this drum. The clutch 60 is then closed and this drives the sprocket chain 57 which imparts rotation by power to the roller 21. As soon as the cloth has been completely wrapped upon it, the roller 21 may be removed by pulling spindle 25 outwardly through the medium of its head 27.

It is understood that the embodiment of the invention set forth herein is only one of the many embodiments or forms the invention may take, and I do not wish to be limited in the practice of the invention nor in my claim to the particular embodiment set forth.

What I claim is:

In an apparatus for sponging cloth, having a belt-driven sponging cylinder, and a

wheel rigid with the cylinder, the combination of a lever pivotally mounted on the frame, having a downwardly extending arm, a pulley carried thereby and engaging the belt to tighten the same, said lever having a brake attached to its upper part in a position to engage the face of the wheel, and means for locking said lever in a position to hold the pulley against the belt and the brake out of contact with the wheel, and for holding the brake against the wheel and the

pulley off of the belt, means tending to hold said lever in the last named position, and a treadle for releasing said locking means.

In testimony whereof I have hereunto set 15 my hand in presence of two subscribing witnesses.

LOUIS BAJETT.
